W. C. BRIDGES,
RAZOR GUARD,
APPLICATION FILED DEC. 21, 1914.

1,247,787.

Patented Nov. 27, 1917.

UNITED STATES PATENT OFFICE.

WILLIAM C. BRIDGES, OF MUSCATINE, IOWA.

RAZOR-GUARD.

1,247,787.

Specification of Letters Patent. Patented Nov. 27, 1917.

Application filed December 21, 1914. Serial No. 878,352.

To all whom it may concern:

Be it known that I, WILLIAM C. BRIDGES, a citizen of the United States, residing at Muscatine, in the county of Muscatine and 5 State of Iowa, have invented certain new and useful Improvements in Razor-Guards, of which the following is a specification.

My invention relates to new and useful improvements in a razor guard.

10 The primary object of the invention is the provision of a razor guard whereby a person may shave his own neck.

A further object of the invention is the provision of means whereby the guard may 15 be secured in proper position on the head.

A still further object of the invention is the provision of means for adjusting the guard.

With these and other objects in view the 20 invention consists in the novel details of construction and arrangement of parts which will be more clearly understood from the following description and drawings, in which,

25 Figure 1 is a view in side elevation showing the guard applied.

Fig. 2 is a front view of the guard.

Fig. 3 is a fragmental face view of the spacing member.

30 Fig. 4 is a fragmental edge view of the spacing member, and

Fig. 5 is a section on the line 5—5 of Fig. 2.

In carrying out my invention it is my 35 desire to provide a guard which may be easily attached to the head in such a position that the neck may be easily shaved and also the provision of means whereby the guard may be adjusted to provide for different shaped heads.

40 In the drawings, the numeral 1 indicates a plate, the ends of which are bent to form eye members to receive the metal loops 2.

A stud or projection 3 is formed on the plate 45 and the purpose of which will be presently described. A band 4 of any desired material is connected to the loop members 2 and extends around the head and forehead, as clearly shown in Fig. 1, of the drawings.

50 The guard proper comprises the plates 5 and 6, the ends of which are adapted to overlap. The plate 5 is provided with the

two headed projections 7 and the plate 6 is provided with the two bayonet slots 8 which are adapted to receive the headed projections 7. Each of the plates 5 and 6 are provided with the extensions or fingers 9 the purpose of which will be presently described. The plate 5 is not provided with the extensions or fingers 9 for a distance 55 from that end of which the plate 6 overlaps. It will be seen, however, that the extensions or fingers 9 of the plate 6 fill this space when the two plates are in position for use.

The plates 5 and 6 are each provided with 60 the elongated slot 10 and extension plates 11, having ear loops 12, said extension plates overlapping the ends of the plates 5 and 6. The extensions 11 are provided with a single extension or finger 13 which will assume a 65 position in alignment with the projections or fingers 9 on the plates 5 and 6 when the several members are in position. Screws 14 pass through the elongated slots 10 and engage threaded openings in the extension 70 plates 11. By these screws and slots the extension plates may be adjusted into various positions.

For spacing the guard plates 5 and 6 in proper relation to the plate 1 I provide a 80 spacing strip 15 the lower end of which is flared, at 16, and said spacing strip is provided near the upper end with a plurality of vertically spaced openings 17. Headed projections 18 are formed on the flared end 85 of the strip 15 and are adapted to engage the upper edge of the plates 5 and 6, as more clearly shown in Fig. 2 of the drawings. The vertically spaced openings 17 are adapted to receive the projection 3 formed on the 90 plate 1 and by engaging the projection 3 with the different openings 17 the space between the plate 1 and guard plates 5 and 6 is varied.

It will be understood that the ear loops 12 95 are preferably covered with rubber or any other suitable material thereby preventing abrasion of the ear.

Having fully described the detailed construction of my device it is thought that the 100 advantages and mode of operation will be clearly understood. When it is desired to use the guard the plates 5 and 6 are brought together so that the ends will overlap and

the headed studs or projections 7 are engaged in the bayonet slots 8. The extension plates 11 carrying the ear pieces 12 are adjusted into proper position by means of the 5 elongated slots 10 and screws 14 and the end pieces engage the ears, as shown in Fig. 1 of the drawings. The plate 1 is then placed in the proper position on the back of the head and held in such position by 10 means of the band 4. The spacing strip 15 is then placed in position with the headed projections 18 engaging the upper edge of the plates 5 and 6 and one of the openings 17 engaging the projection 3 on the plate 1. It 15 will therefore be seen that the plates 5 and 6 engage the head in such a position that the neck may be easily shaved. In shaving, the razor will assume the position indicated in dotted lines in Fig. 1 of the drawings and 20 the extensions 9 on the plates 5 and 6 limit the upward movement of the razor. After the guard has been used it can be easily removed by taking off the spacing strip 5, removing the plate 1 and then removing the 25 ear loops from the ears. When not in use the plates 5 and 6 may be disconnected by removing the studs 7 from the bayonet slots 8. If desired, after the extension plates 11 have been once adjusted they may be left 30 in their adjusted positions. As indicated in the drawings, the plates 5 and 6 are curved in order that they will conform to the curvature of the head and neck.

Having fully described the invention 35 what I claim as new and desire to secure by Letters Patent is:—

1. A razor guard comprising a longitudinally curved plate having guard finger extensions on the upper edge thereof, said extensions having their terminals bent outward to provide a stop for the razor, and means for securing the guard in position.

2. A razor guard comprising a curved plate having extensions on the upper edge thereof, extension strips adjustably connected to the plate and provided with extensions on the upper edge thereof, and ear loops formed on the ends of the extension strips.

3. A razor guard comprising a sectional longitudinally curved plate substantially semi-circular in formation, means for connecting the sections, a plurality of guard fingers, extensions formed on the upper edge of the sections, the terminals of said guard fingers being bent outward at substantially right angles to provide a stop for the razor, and means for securing the guard in position.

4. A razor guard comprising a curved plate, a band adapted to encircle the upper portion of the head, a projection formed on the band, a strip provided with a perforation adapted to receive the projection on the band, and extended substantially perpendicular to the plane of the band, and

headed projections formed on the strip and adapted to engage the upper edge of the curved plate at an intermediate portion thereof.

5. A razor guard comprising a curved plate, a band adapted to encircle the upper portion of the head, a projection formed on said band, a strip provided with a plurality of vertically spaced openings adapted to receive the projection on the band and to extend substantially perpendicular to the plane of the band, and headed projections formed in the lower end of the strip and adapted to engage the upper edge of the curved plate, at an intermediate portion thereof.

6. A razor guard comprising a curved plate, a plate provided with a projection, a band secured to said second plate and adapted to encircle the head, and a spacing strip connecting the curved plate and second plate and extending substantially perpendicular to the plane of both.

7. A razor guard comprising a curved plate having a plurality of projections formed on the upper edge thereof, a band adapted to encircle the head, a projection formed on said band, a spacing strip provided with a plurality of vertically spaced perforations adapted to receive the projection on the band, and headed projections formed on the lower end of the spacing strip and adapted to engage the upper edge of the curved plate between the projections.

8. A razor guard comprising a sectional curved plate, one of said sections provided with headed projections and the other section provided with elongated openings adapted to receive the projections, extensions formed on the upper edge of each section, an ear loop adjustably connected to each section, a band adapted to encircle the head, a projection formed on the band, and a spacing strip connected to the band and curved plate, said spacing strip provided with a plurality of vertically spaced openings adapted to receive the projection on the band, and headed projections near the lower end thereof adapted to engage the upper edges of the sections of the curved plate.

9. A razor guard comprising a curved plate formed in two sections, one of said sections provided with headed projections and the opposite section provided with elongated slots adapted to receive the headed projections, right angle extensions formed on the upper edge of each section, extension strips adjustably connected to and overlapping the ends of the sections of the curved plate, right angle extensions formed on the upper edge of the extension plates, ear loops formed on the extension strips, a band adapted to encircle the head, a projection formed on said band, and a spacing strip

connected to the band and curved plate,
said spacing strip provided with a plurality
of vertically spaced openings to receive
the projection on the band, and headed
projections formed on the lower end
thereof adapted to engage the upper edge
of the curved plate between the projections.

In testimony whereof I affix my signature
in presence of two witnesses.

WILLIAM C. BRIDGES.
